United States Patent

Des. 238,575

Patented Jan. 27, 1976

238,575

TELEPHONE LIST FINDER

Chuzo Mori, Tokyo, Japan, assignor to Carl Manufacturing Company Ltd., Tokyo, Japan

Filed May 30, 1974, Ser. No. 474,413

Term of patent 14 years

Int. Cl. D19—02

U.S. Cl. D19—76

FIG. 1.

FIG. 3.

FIG. 2.

FIG. 4.

FIG. 5.

FIG. 6.

FIG. 1 is a top plan view of a telephone list finder embodying my new design;

FIG. 2 is a front elevational view thereof;

FIG. 3 is a rear elevational view thereof;

FIG. 4 is a bottom plan view thereof;

FIG. 5 is a left side elevational view thereof; and

FIG. 6 is a right side elevational view thereof.

I claim:

The ornamental design for a telephone list finder, substantially as shown.
